MULTIPLE STAGE STEAM TURBINE

William Anthony Jones, West New Brighton,
N. Y.

Application August 29, 1932. Serial No. 630,867

6 Claims. (Cl. 60—73)

When steam expands adiabatically it may perform useful work which is the mechanical equivalent of the difference in total heat of the steam before and after the expansion. The total heat 5 of the steam is the sum of that due to the latent heat and that due to the sensible heat.

At high pressure saturated steam has been latent heat and more sensible heat than does saturated steam at lower pressure.

10 When steam expands through a nozzle attaining a velocity of flow and this velocity is dissipated by friction into heat in a closed vessel, as in a calorimeter, the energy of motion is converted into heat and the resulting temperature 15 of the steam at the lower pressure depends upon how much moisture if any is in the steam before expansion.

If no moisture is initially present, the steam at the lower pressure, in general, will be superheated somewhat above the temperature of saturated steam at the lower pressure. Calorimeters made on this principle enable us to determine small amounts of moisture in steam at high pressure.

25 When steam expands within a multiple stage turbine, it first loses its superheat, if any, and then part of its latent heat with resulting condensation of part of the steam into water.

In the later stages of the multiple stage turbine 30 this water does not attain the velocity which the expanding steam attains and as a result the water is churned by the turbine blades with accompanying friction which tends to reevaporate the water as in a calorimeter, so that the difference 35 in total energy of the steam, before and after passing through the turbine, which is equivalent to the mechanical work performed, is less than it otherwise would be.

In the past engineers have sought to avoid this 40 condition, first, by using a high degree of superheat in the entering steam to prevent condensation in the early stages of the turbine, and second, by resuperheating the steam at a lower pressure to prevent condensation in the later stages of 45 the turbine.

This practice does not decrease the total heat per pound of steam that is discarded in the exhaust, as is obviously necessary for the highest efficiency, and it has the further disadvantage 50 of requiring expensive apparatus and space and much piping, which causes loss of pressure further decreasing efficiency, and of requiring special materials to withstand the very high temperatures used.

55 Resuperheating the steam as described also has

the disadvantage that the volume of the low pressure steam is materially larger than it would be if part of the steam was condensed and the steam was not resuperheated and this in turn requires larger turbines, piping, condensers, more building and more space than would otherwise be required for a given power generated.

My invention takes advantage of the higher efficiency of condensation with its smaller volumes, lower temperatures and simpler apparatus by the 60 following means:

When flowing steam containing moisture is deflected and has its direction of motion changed by a surface, any particles of moisture in the steam, by reason of their greater weight and 70 inertia, tend to continue their motion in straight lines and are brought into intimate contact with the deflecting surface.

If the deflecting surface is maintained at a 75 temperature slightly above the boiling point of water at the particular pressure of the flowing steam at that part of the turbine, then the moisture will be reevaporated into steam.

The fact that a very slight difference in temperature between a surface and a vapor, enables 80 a great quantity of heat to be imparted to the surface by condensation of the vapor when the surface is at a lower temperature, or from the surface by evaporation of a liquid into vapor when the surface is at a higher temperature, enables us 85 to condense steam at one side of a plate of metal and to evaporate water into vapor at the other side of the plate of metal with a very slight difference in temperature between the vapors on the 90 two sides of the plate.

In my invention the deflecting vanes of a turbine are heated by steam of a higher pressure than the flowing steam taken from the multiple stage steam turbine at a stage above that of the flowing steam, with the result that as the steam flows through the many stages of the turbine, these heated vanes are always hotter than the steam which flows in contact with their surfaces.

These heated vanes are at a lower temperature than the heating steam.

The heated vanes are hotter than the flowing steam and cooler than the heating steam so that they condense steam at one of their surfaces and evaporate water at their other surface, thus permitting the condensation of part of the steam as it flows through the turbine and keeping the resulting water separate from the flowing steam so that the water is not churned by the turbine blades and reevaporated into steam.

It is of course possible to use high pressure 110

steam to maintain the temperature of the deflecting surfaces but to do so does not give an efficiency as high as is attained by using steam from a higher stage of the turbine because it discards more heat in the exhaust. It would also 5 require stronger construction.

Using high pressure live steam for heating the hollow vanes does not take advantage of the mechanical work which that steam might do before it is used for heating. When steam for heating the deflecting surface is taken from a higher stage of the turbine, that steam has already imparted some of its energy to the turbine in the form of mechanical work, before it imparts the remainder of its available energy in the form of 10 heat to the deflecting surfaces.

Keeping the water, resulting from condensation of the steam, separate from the steam, has the further advantage of decreasing the erosion of the turbine blades which occurs in the lower 20 stages of existing turbines, where most water is present in the steam and particularly at their outer radius where water is concentrated by centrifugal action as it passes through the turbine.

Referring to the accompanying drawings:

Fig. 1 is a vertical longitudinal section of a 25 multiple stage steam turbine illustrating my invention.

Fig. 2 is a part section on line AA of Fig. 3 through moving blades and steam heated hollow 30 stationary vanes, at a larger scale.

Fig. 3 is an enlarged part of Fig. 1, showing a section through the casing, moving blades and steam heated stationary vanes.

Fig. 4 is a part section on line BB of Fig. 3 through casing and steam heated stationary 35 vanes.

Fig. 5 is a part section on line AA of Fig. 3 through a steam heated stationary vane showing 40 welded joints.

Fig. 6 is a part section on line CC of Fig. 5 of a steam heated stationary vane showing welded 45 joints.

Fig. 7 is a part section on line DD of Fig. 6 of a steam heated stationary vane showing welded 50 joints.

Fig. 8 is a part section on line EE of Fig. 6 of a steam heated stationary vane showing welded 55 joints.

Fig. 9 is a part section on line FF of Fig. 6 of a steam heated stationary vane showing welded 60 joints.

Fig. 10 is a diagram in which line, 30—31, represents the steam velocity entering the wheel, line, 32—33, represents the velocity of the wheel, line, 30—34, equal to line, 31—35, is relative velocity of steam to wheel entering and leaving the wheel, line, 34—35, represents velocity, relative to the earth, of steam leaving the wheel and entering the space between the following stationary vanes where the steam again acquires velocity at the expense of pressure and heat.

Fig. 11 is a part longitudinal section through moving blades and stationary vanes of a multiple 65 stage turbine of the usual construction with cylindrical, instead of conical, surfaces at the inner and outer radii of the steam passages in the wheel resulting in more friction and eddies in the steam flow and generating more heat, with loss of pressure, than the continuous conical surfaces of my 70 invention.

Fig. 12 is a Mollier diagram for convenience in visualizing the increase in efficiency resulting 75 from keeping the water resulting from condensation separate from the flowing steam and in

visualizing the increase in efficiency resulting from the construction shown in Figs. 1, 3, and 4 eliminating ripples in steam flow resulting from the crooked passages and construction shown in Fig. 11.

Like reference characters indicate like parts in the several views.

In the turbine shown, which I have chosen for purposes of illustration, a shaft, 1, supported by bearings, 2 and 3, carries rotating discs, 4, on whose edges moving blades, 5, are driven by jets of steam flowing between stationary vanes, 6.

Stationary vanes, 6, are in the form of curved rectangular tapered tubes formed of curved radial plates, 41 and 42, and circumferential outer and 90 inner plates, 43 and 44, which are conical.

Plates, 41, are curved to a shorter radius than plates, 42, so that a space, 8, is formed between them and connects space, 7, in piece, 9, outside of stationary vanes, 6, with space, 10, in piece, 95 11, inside of stationary vanes, 6.

Stationary vanes, 6, are welded, or otherwise attached, to outer piece, 9, and to inner piece, 11, and to each other so that spaces, 7, 8 and 10, are completely enclosed and steam within these spaces 100 completely surrounds rectangular tubular stationary vanes, 6.

Pipes, 12, valves 13 and pipes, 14, conduct steam from spaces, 15, beyond rotating discs at one stage to spaces, 7, 8 and 10, at a lower stage, so 105 that rectangular tubular stationary vanes, 6, of one stage are completely surrounded by steam at a higher pressure and temperature from an earlier stage of the turbine.

Pipes, 16, valves, 17, and pipes, 18, at the lower 110 side of the turbine, connect spaces, 7, of one stage with space, 7, of a lower stage and are available to drain water from condensed steam, from one stage to a stage below.

Valves, 13 and 17, will be adjusted to maintain 115 the desired pressure in spaces, 7, 8 and 10, and so that only water from condensed steam and no steam itself will flow through valve, 17.

Evidently steam within spaces, 7, 8 and 10, surrounding vanes, 6, will be at a higher pressure 120 and temperature than the flowing steam which drives the turbine blades, 5, at that point and the metal of the stationary vanes, 6, at that point will be at an intermediate temperature, so that steam in spaces, 7, 8 and 10, will be condensed supplying 125 heat to prevent condensation in the flowing steam and evaporating any moisture that may be in the flowing steam. This is the object desired.

Steam enters the turbine through ports, 20, 130 and for high ratings through ports, 21. Steam is exhausted to space, 22.

Condensed steam, forming water separate from the flowing steam, is finally discharged through valves, 19, and ordinarily will be returned to the 135 boiler feed.

If parts are made of steel they may be conveniently joined by electric welding, which is the construction contemplated in the particular representation shown. Edges may be beveled so 140 that the welding metal will completely seal the joints between pieces, 9, 11, 41, 42, 44 and 45, as shown.

Evidently the number of vanes per stage and the length of the vanes axially may be varied to 145 give somewhat more than the required heating surface for each stage.

In the Mollier diagram, Fig. 12, line AF represents the adiabatic expansion of steam, without friction, from about 380 pounds absolute pres- 150

sure and 676 degrees F. temperature, having about 1350 B. t. u. total heat above 32 degrees and entropy about 1.6342, expanding to an absolute pressure of 1 inch of mercury where by weight there will be 79.3 per cent of steam and 20.7 per cent of water and the total heat above 32 degrees F. will be about 877.86 B. t. u., giving a theoretical efficiency above 32 degrees of 1350 minus 877.86 divided by 1350 equals about 35 per cent.

Line ABC represents the expansion of this steam to the same final pressure in a turbine where water of condensation is not separated from the flowing steam and as a result of friction the exhaust is assumed to have 982 B. t. u. per pound above 32 degrees F. giving an efficiency about equal to 1350 minus 982 divided by 1350 equals about 27.25 per cent.

Line ABD represents the expansion of this steam to the same final pressure in a turbine where water of condensation is kept separate from the flowing steam as described in this application and the exhaust is assumed to have 956 B. t. u. per pound above 32 degrees giving an efficiency about equal to 1350 minus 956 divided by 1350 equals about 29.2 per cent.

27.25 divided by 29.2 gives .935 as much steam for line ABD as for line ABC for the same power.

Line AE represents the expansion of this steam to the same final pressure in a turbine where water of condensation is kept separate from the flowing steam as described and with an assumed friction of flow one half as great as that for line AD due to elimination of ripples, shown in Fig. 3, 11, and using the construction shown in Fig. 3, so that the exhaust has only 917 B. t. u. per pound giving an efficiency about equal to 1350 minus 917 divided by 1350 equals about 32.07 per cent.

27.25 divided by 32.07 gives 85 per cent as much steam for line AE as for line ABC for a given power.

The foregoing figures are assumed simply as an illustration.

I claim:

1. In combination, in a multiple stage steam turbine, a steam inlet, a shaft with bearings, a casing, rows of moving blades carried by the shaft, rows of hollow stationary vanes between the rows of moving blades, the stationary vanes and the moving blades being formed between concentric inner and outer surfaces whose longitudinal sections are approximately straight lines, connections conducting some steam from a separate upper stage to heat the hollow vanes of each lower stage where it is condensed and supplies heat to those hollow vanes and thereby to the flowing steam of lower pressure and temperature at that point, connections conducting only the water from this condensation, and no steam, from each row of hollow stationary vanes in succession to rows of hollow stationary vanes below.

2. In combination, in a multiple stage steam turbine, a steam inlet, a shaft with bearings, a casing, rows of moving blades carried by the shaft, rows of hollow stationary vanes between the rows of moving blades, connections conducting some steam from a separate upper stage to heat the hollow vanes of each lower stage and connections conducting only water, condensed from this heating steam, in succession to the hollow stationary vanes of each stage below.

the rows of moving blades, connections conducting some steam from a separate upper stage to heat the hollow vanes of each lower stage where it is condensed and supplies heat to those hollow vanes and thereby to the flowing steam of lower pressure and temperature at that point, connections conducting only the water from this condensation, and no steam, from each row of hollow stationary vanes in succession to rows of hollow stationary vanes below, valves in the water connections, whereby the flow can be controlled, valves in the steam connections, whereby the heating of the vanes can be controlled and changed to suit the rate at which the turbine is working and the point at which saturation of the steam occurs.

3. In combination, in a multiple stage steam turbine, a steam inlet, a shaft with bearings, a casing, rows of moving blades carried by the shaft, rows of hollow stationary vanes between the rows of moving blades, connections conducting some steam from a separate upper stage to heat the hollow vanes of each lower stage where it is condensed and supplies heat to those hollow vanes and thereby to the flowing steam of lower pressure and temperature at that point, connections conducting only the water from this condensation, and no steam, from each row of hollow stationary vanes in succession to rows of hollow stationary vanes below, valves in the water connections, whereby the flow can be controlled.

4. In combination, in a multiple stage steam turbine, a steam inlet, a shaft with bearings, a casing, rows of moving blades carried by the shaft, rows of hollow stationary vanes between the rows of moving blades, connections conducting some steam from a separate upper stage to heat the hollow vanes of each lower stage where it is condensed and supplies heat to those hollow vanes and thereby to the flowing steam of lower pressure and temperature at that point, connections conducting only the water from this condensation, and no steam, from each row of hollow stationary vanes in succession to rows of hollow stationary vanes below.

5. In combination, in a multiple stage steam turbine, a steam inlet, a shaft with bearings, a casing, rows of moving blades carried by the shaft, rows of hollow stationary vanes between the rows of moving blades, arrangements by which at each lower stage a portion of the expanding steam is separated from the main body of the expanding steam and the condensations of these separated quantities of steam and the resulting water supply heat in succession to the lower stages of the cooler expanding steam, thus giving the advantage of condensation in higher efficiency and smaller volumes and avoiding the disadvantage of churning the water of condensation, as described.

6. In combination, in a multiple stage steam turbine, a steam inlet, a shaft with bearings, a casing, rows of moving blades carried by the shaft, rows of hollow stationary vanes between the rows of moving blades, connections conducting some steam from a separate upper stage to heat the hollow vanes of each lower stage and connections conducting only water, condensed from this heating steam, in succession to the hollow stationary vanes of each stage below.

WILLIAM ANTHONY JONES.
